[57] CLAIM

The ornamental design for a covered geriatric's dish, as
shown and described.

DESCRIPTION

FIG. 1 is a top, front perspective view of a covered
geriatric's dish showing my new design;

FIG. 2 is an exploded top, front, perspective view
thereof;

FIG. 3 is a top plan view of the dish thereof;

FIG. 4 is a front elevational view of the dish of FIG. 3;

FIG. 5 is a bottom plan view of the dish of FIG. 3;

FIG. 6 is a top plan view of the cover thereof;

FIG. 7 is a side elevational view of the cover of FIG. 6;

FIG. 8 is a bottom plan view of the cover of FIG. 6;

FIG. 9 is a cross-sectional view thereof in elevation
taken on line 9—9 of FIG. 1 on an enlarged scale;

FIG. 10 is a cross-sectional view thereof, taken on line
10—10 of FIG. 3 on an enlarged scale; and

FIG. 11 is a front elevational view thereof of FIG. 1.
